CLAIM

The ornamental design for a dispenser for detergent or
the like, as shown and described.

DESCRIPTION

FIG. 1 is a front elevational view of a dispenser for
detergent or the like showing my new design;
FIG. 2 is a left side elevational view thereof;
FIG. 3 is a right side elevational view thereof;
FIG. 4 is a rear elevational view thereof;
FIG. 5 is a top view thereof; and
FIG. 6 is a bottom view thereof.
